CLAIM

I claim the ornamental design for a glass and cooling or warming sphere, as shown.

DESCRIPTION

FIG. 1 is a front perspective view of a glass and cooling or warming sphere showing my new design;

FIG. 2 is a left side elevational view thereof;

FIG. 3 is a front elevational view thereof;

FIG. 4 is the right side elevational view thereof;

FIG. 5 is the rear elevational view thereof;

FIG. 6 is a top plan elevational view thereof; and,

FIG. 7 is the bottom plan elevational view thereof.

The broken lines shown in the figure drawings are included for the purpose of illustration and form no part of the claimed design.
